UNITED STATES PATENT OFFICE.

AMOS JOHNSON, OF BALTIMORE, MARYLAND.

IMPROVEMENT IN STEERING APPARATUS FOR VESSELS.

Specification forming part of Letters Patent No. 222,406, dated December 9, 1879; application filed October 29, 1879.

To all whom it may concern:

Be it known that I, AMOS JOHNSON, of Baltimore city, State of Maryland, have invented certain new and useful Improvements in Steering Apparatus for Vessels; and I hereby declare the same to be fully, clearly, and exactly described as follows, reference being had to the accompanying drawings, in which—

Figure 1 is a plan view of a steering apparatus embodying my invention. Fig. 2 is a side elevation (enlarged) of one of the adjustable pulleys.

The object of my invention is to furnish a steering apparatus by means of which the helm may be readily and expeditiously shifted, and one which will remain in any position to which it is brought without liability of shifting or twitching the wheel out of the helmsman's grasp as a sea, rising under the vessel's counter, strikes the rudder.

Various means have been proposed for securing the helm in any desired position; but they have all of them been open to the objection that they had to be cast loose again before the helm could be moved. With the device about to be described this is not the case. As before stated, the rudder will stay in any position to which it is brought; but, the wheel not being secured, the rudder may be immediately moved as may be desired upon turning the wheel. This feature of my invention renders it especially applicable on short-handed craft.

When it is desired to go about, the helmsman simply puts the helm hard down, and is free to assist the rest of the crew in swaying round the head-yards as the ship comes up in the wind. With the ordinary wheel this cannot be done, as, unless the wheel is lashed a-lee, the rush of the water would bring the rudder back amidships and the ship would miss stays.

The helmsman's assistance will frequently enable the watch on deck to perform labor which, without him, would necessitate the calling of all hands, greatly to the discomfort of those below. In such cases the helmsman simply steadies the ship on her course, and leaves the wheel to assist the crew, in the consciousness that the ship will steer herself un-

til his return, or at least that he will find the helm in the position in which he left it.

Besides this, my invention greatly lessens the labor of steering, as the helmsman need not touch the wheel except to bring the ship back to her course as she yaws aways, and the continual strain and pulling and hauling incident to the use of the old-fashioned wheel, which was liable to spin around with every sea that struck the rudder, are obviated.

In the accompanying drawings, A is the wheel, mounted, as usual, on stanchions *a a*, bolted to the deck. On its shaft are secured two drums, B B', of different diameter, on which are coiled the chains *b b'*, the same being wound on the drum B in the opposite direction to that on the drum B', being, in a word, a simple differential wheel and axle.

To the rudder-head C is firmly bolted a sector, *e*, having two parallel grooves in its face for the pennant-chains D. These are led in opposite directions around the sector and rudder-head, and firmly bolted to the latter.

Blocks *e' f' e' f'* are bolted to the deck at either side of the wheel close up to the taffrail, and the whole device, with the exception of the wheel, is preferably housed in to prevent the chains and running-gear from rusting, one or more scuttles being made in the housing, so that access may be had to the steering-gear for repairs should anything part or get out of order. The chains *b b'* are led, as shown, once or twice around the drum B', thence through the aftermost blocks on deck and through the pennant-blocks *d*, and thence through the blocks *e' f'* and around the drum B in the opposite direction to that on the other drum.

With regard to the relative proportions of the parts I have found in practice that about two to two and a half revolutions of the wheel should suffice to put the helm hard up or down—that is, at about an angle of forty-five degrees with the keel. Beyond this it should never go, as it deadens the ship's way without exerting any greater effect in directing her course, being on the contrary less effective.

The pennant-chains D are, as stated, led around the rudder-head and clinched thereto, so that in case the sector should be wrenched off control of the helm is maintained, the slack

of the chains being taken up by a turn or two round the rudder-head.

The blocks *e' e* are made adjustable, so as to take up slack as the chains wear, and are, by preference, constructed as shown in Fig. 2, where *E* is a plate secured to the deck by means of a bolt, *F*. On the plate *E* the housing of the sheave *e' e* slides, being clamped at any point by means of the screw *G*, which incidentally serves as the sheave-pin.

As will have been perceived, the purchase on the rudder is immense; but the construction of the parts is such that while the helm is quickly and easily shifted it will stay wherever it is placed—a feature the advantages of which will have been appreciated.

Instances frequently occur in which it is of great importance that the helmsman be able to leave the wheel for an instant, as in case of a man falling overboard while the ship is under rapid way. Before any one forward or amidships can cast loose a rope the ship will have run so far as to prevent its being thrown within the reach of the man in the water. The helmsman, being aft, however, has the time at his disposal while the ship is running, on the average, half her length to cast loose the slack of a brace or the spanker-sheet and throw it to the man overboard.

With a ship, however, that carries a strong helm, either weather or lee, it will not do, if she is equipped with an ordinary wheel, for him to let go of it for an instant; or if he does and the ship be close to the wind, he is liable to find her all aback and broached to. With a wheel that will stay where it is put, no danger is to be apprehended, as, even if the ship be as close to the wind as she will draw, it is only necessary to spin the wheel a half-turn to windward to avoid all danger of her broaching to.

My invention is also of importance on such ships of war as are not steered by steam-power, in view of the possible contingency of the killing of the helmsman when the ship is in action.

What I claim as new, and desire to secure by Letters Patent, is—

In combination with the drums *B B'*, the chains *b*, blocks *e', f', e, f*, and *d*, pennant-chains *D*, and sector *c*, the pennant-chains being led in opposite directions around the sector and rudder-head, as set forth.

AMOS JOHNSON.
